UNITED STATES PATENT OFFICE.

ROBERT W. MACDONALD, OF CHICAGO, ILLINOIS, ASSIGNEE TO WUNDUR CABINET LEDGER COMPANY, OF CHICAGO, ILLINOIS, A CORPORATION OF ILLINOIS.

LEDGER CABINET.

Application filed April 5, 1920. Serial No. 371,274.

To all whom it may concern:

Be it known that I, ROBERT W. MACDONALD, a citizen of the United States, residing at Chicago, in the county of Cook and State of Illinois, have invented certain new and useful Improvements in Ledger Cabinets, of which the following is a specification.

This invention relates to a ledger cabinet such as is adapted to receive leaves or cards on which is contained any desired data; more particularly it is concerned with certain improvements in a cabinet structure by which its usefulness is enhanced and its conversion from one purpose to another is facilitated. The invention has also a number of other objects all of which will appear from the detailed description to follow wherein reference is made to the accompanying drawing which illustrates an exemplification of this invention in the manner following:

Figure 1 is a side elevation of the cabinet; Fig. 2 is a plan view thereof;

Fig. 3 is a longitudinal section taken on line 3—3 of Fig. 2;

Fig. 4 is a transverse section taken on line 4—4 of Fig. 1;

Fig. 5 is a fragmentary vertical section taken on line 5—5 of Fig. 3; and

Fig. 6 is a face view of one of the cards or leaves adapted to be received within the cabinet.

As shown in the drawing, the cabinet or box may be constructed with a base 10 from which upstand ends 11 and 12 between which is a fixed side 13 and a removable side 14. It is preferred that the corners of the box be reinforced as by means of angle plates 15, those which overlie the side 13 being fixedly secured thereto and to the proximate end, and those which overlie the removable side 14 being secured to the ends only. In this manner an outer stop for the removable side is provided. Within the cabinet so formed may be received a stack of cards or leaves 16 which lie in adjacent relation to the removable side to form an inner stop therefor (see Fig. 2). Interiorly of the box at each end is arranged a block 17 extending from side to side and provided with a base of substantial width, the inner face of each block being slanted outwardly, as shown in Fig. 3. The effect of these two blocks so arranged is to provide abutments for the stack

of leaves or cards so that they may incline 55 either way, as desired.

The removable side 14 is preferably equipped with a handle 18 to facilitate raising manipulations thereof. By preference its upper and lower edges are grooved as at 19 so as to guide the removable side in a sliding movement adjacent the outer side of the end 12 adjacent to which is provided on an extension of the base, a rib 20 adapted to cooperate with the lower groove 19. In alignment with this rib is a lip 21 adapted to cooperate with the upper groove 19 of the side 14, this lip being carried upon a head 22 that is formed as part of a vertically movable plate 23 that may be received within a mortise that is formed within the proximate block 17, all as best indicated in Fig. 3. This plate 23 is guided in its movements as by means of screws 24 which are entered through slots 25 formed in the plate and secured to the end wall 12. Normally the plate 23 is held in a downward position as by means of one or more springs 26 which, if desired, may be of the form shown best in Fig. 5. At its lower end the plate is slotted 75 as at 27 to provide a yoke which is adapted to lie over the neck 28 of a lock rod 29 having a pointed head 30 at its extremity, the other end of the rod being shaped in the form of an eye 31. This lock rod extends 80 longitudinally through the cabinet adjacent its base, suitable openings being provided within the abutment blocks for this purpose. The bar also passes through an opening 32 formed in each card or leaf of the stack so as 90 to lock the same in place. Preferably these leaves are formed with two or more such openings arranged in a definitely spaced relation permitting certain of the leaves, if desired, to be offset with respect to the others, while still traversed by the rod. In Fig. 6 the leaves are shown to be provided also with two notches 33, preferably arranged equidistantly between the openings 32, one such notch in each card or leaf being adapted to register with a rib 34 that projects upwardly from the base of the cabinet adjacent the removable side thereof.

In use the leaves may be arranged within the cabinet, as shown in Figs. 1 and 2, all 105 aligned and locked in position. If however, it is desired to offset certain of these leaves, the side 14 may be removed and then slipped

in place under the lip 21 whereupon the head 22 will be raised against the influence of the spring 26, the lower edge of the side 14 being held upon the base with its rib 20 entered in the groove 19. Under the action of the spring 26 the removable side is held firmly upon the end of the cabinet, but without preventing sliding movements thereof to any point desired. In Fig. 4 I have represented in dotted lines the side 14 arranged upon the end of the cabinet in an overlapping relation such as to provide protection for the offset leaves which are indicated by dotted lines in this figure.

15 It will be noted that when the side 14 is in end position, the plate 23 is held in raised position such that it becomes ineffective to prevent removable of the rod 29. This may accordingly be withdrawn freely to permit the leaves or cards to be offset in any manner that is desired. By means of the rib 34 and notches 33 a desired distance of offset may be accurately and readily determined.

25 The invention which I have herein shown and described is one which is very simple in construction and use. It embodies the novel features of a compact cabinet which may be used in the ordinary manner, or which may be used with offset leaves. The side 14 which is removable in the manner explained acts not only as a protection for the offset leaves when secured in end position, but it cooperates with the locking means for the rod in such a manner that the latter may always be withdrawn whenever the side 14 is in end position. It is obvious, of course, that the invention may be embodied in forms other than the one herein shown, and in respect of any changes or modifications that may embody the novel features hereinafter claimed, I desire that the same be included within the scope of this patent.

I claim:

- 45 1. A ledger cabinet having in combination a base from which upstands two ends and a side all in fixed unitary relation, the cabinet so formed being adapted to receive a quantity of leaves, a second side extending between the ends and completing the enclosure for the leaves, means including the leaves for holding the second side removably in place, means for locking the leaves within the cabinet, a device which normally prevents unlocking of said locking means, and means for holding the removable side in a second position upon the cabinet, said latter means having connection with the device which normally prevents unlocking of the locking means, and acting when holding the removable side in its second position to permit freely unlocking of said locking means whereby the leaves may be withdrawn from the cabinet, substantially as described.
- 60 2. A ledger cabinet having in combination a base from which upstands two ends and a side all in fixed unitary relation, the cabinet so formed being adapted to receive a quantity of leaves, a second side extending between the ends and completing the enclosure for the leaves, means including the leaves for holding the second side removably in place, means for locking the leaves within the cabinet, a device which normally prevents unlocking of said locking means, and means for holding the removable side in a second position upon the cabinet, said latter means having connection with the device which normally prevents unlocking of the locking means, and acting when holding the removable side in its second position to permit freely unlocking of said locking means whereby the leaves may be withdrawn from the cabinet, substantially as described.
- 65 3. A ledger cabinet having in combination a base from which upstands a side and two ends all in fixed unitary relation, a second side adapted to be removably received between the ends to provide an enclosure for a quantity of leaves, a lock rod arranged longitudinally within the cabinet and adapted to pass through each leaf to hold the same in place, means exteriorly of one cabinet end for holding the removable side when arranged adjacent thereto, said means including an element which co-operates with the locking rod to normally prevent its withdrawal from the cabinet and which when engaged with the side to hold it in end position is rendered inoperative to prevent such withdrawal, substantially as described.

3. A ledger cabinet having in combination a base, two ends, and a side all in fixed unitary relation, a second side adapted to be removably received between the ends to provide an enclosure for a quantity of leaves, a lock rod arranged longitudinally within the cabinet and adapted to pass through each leaf to hold the same in place, means exteriorly of one cabinet end for holding the removable side when arranged adjacent thereto, said means including an element which co-operates with the locking rod to normally prevent its withdrawal from the cabinet and which when engaged with the side to hold it in end position is rendered inoperative to prevent such withdrawal, substantially as described.

3. A ledger cabinet having in combination a base, two ends, and a side all in fixed unitary relation, a second side adapted to be removably received between the ends to provide an enclosure for a quantity of leaves, an abutment block arranged adjacent the inner face of each end, one of said blocks having a channel mortised therein, a movable plate within the channel having at its lower end a yoke, a locking rod extending longitudinally through the cabinet and presenting one of its ends which is formed with a neck operatively to the yoke of the movable plate whereby withdrawal of the rod is prevented when the plate engages the rod, tension means normally holding the yoke against the rod neck, means for preventing withdrawal of the plate from the cabinet, a head carried by the plate in overhanging relation to one cabinet end, and a lip downwardly depending from the head, the base of the cabinet being extended beneath the lip to receive thereon the lower edge of the removable side when arranged adjacent the proximate end of the cabinet, the upper edge of the removable side being formed with a groove into which the lip depends for holding the side adjacent the end of the cabinet, substantially as described.

4. A ledger cabinet in the form of a box adapted to receive a quantity of leaves, one of the box sides being removable from the cabinet, a rod adapted to be extended through the cabinet and through each leaf to lock the leaves in place, spring-actuated means adapted normally to prevent withdrawal of the rod from locking position, and means for supporting said removable side in a second position exteriorly of the cabinet, said supporting means having connection with the spring-actuated means and adapted when affording support for the removable side to retract said means to thereby permit withdrawal of said rod, substantially as described.

5. A ledger cabinet having a base, two ends, a fixed side therebetween, and a movable side therebetween, a quantity of stacked

leaves adapted to rest within their lower edges on the cabinet base to present one vertical edge adjacent the fixed cabinet side, and the other edge against the movable cabinet side when the latter is in one position, each leaf being adapted for offset a definite distance with respect to the remainder of

the leaf stack when the movable side is in another position, and means for engaging with each such leaf to limit its distance of 10 offset, substantially as described.

ROBERT W. MACDONALD.
